TYPEWRITING MACHINE

John L. Petz, Rochester, N. Y., assignor to International Business Machines Corporation, New York, N. Y., a corporation of New York

Application July 24, 1937, Serial No. 155,363

11 Claims. (Cl. 197—153)

This invention relates to typewriting machines.

The broad object of the present invention is to provide an improved ribbon feeding mechanism suitable for the ribbons used in the preparation of carbon copies or for the production of master sheets such as are used in connection with the well known "Ditto" and "New Process" duplicating processes.

Another object is to provide ribbon feeding mechanism in which the ribbon spools and the ribbon feed mechanism are mounted independently of the carriage thereby relieving the usual spring motor and the operator of the work of moving the additional load on the carriage which is usually imposed by the mounting of the ribbon feed mechanism and the ribbon spools on the carriage.

Another object is to provide a ribbon feeding mechanism which is mounted independently of the carriage and operated by the carriage through a flexible connection whereby the ribbon moves in step with the carriage.

An object is to provide a ribbon feeding mechanism which is relatively simple in construction and imposes little additional load upon the usual carriage feeding mechanism and carriage return mechanism.

Further objects of the instant invention reside in any novel feature of construction or operation or novel combinations of parts present in the embodiment of the invention described and shown in the accompanying drawings whether within or without the scope of the appended claims and irrespective of other specific statements as to the scope of the invention contained herein.

In the drawings:

Fig. 1 is a plan view of the machine;

Fig. 2 is an elevation of the rear portion of the left hand side of the machine with reference to Fig. 1;

Fig. 3 is a rear elevation of the machine;

Fig. 4 is an enlarged rear elevation of the feed rollers;

Fig. 5 is a vertical section on the line 5—5 of Fig. 4;

Fig. 6 is an enlarged vertical section on the line 6—6 in Fig. 3;

Fig. 7 is an enlarged plan view of the right hand rear ribbon guide;

Fig. 8 is a right side elevation of the right hand rear ribbon guide;

Fig. 9 is a front elevation of the right hand front ribbon guide.

55 Purely as a matter of convenience in descrip-

tion, the present invention has been illustrated and will be described hereinafter as applied to the well known "International" electric writing machine, formerly known as the "Electromatic". It will be understood, however, that the invention is not limited to use in a power operated typewriter of the type selected for purposes of illustration, but may be used in other machines, whether manually or power operated. Since the "International" electric writing machine is now well known in the art and the various mechanisms comprising same are described in numerous patents, the typewriter will not be described in detail herein.

The numeral 10 designates the base of the machine on which is mounted the usual carriage including end plates 11 and a member 12 (Fig. 2) welded or brazed to the end plates 11. The member 12 is formed with suitable channels or grooves confronting the usual carriage guide rails 13. Anti-friction roller assemblies 14, riding in the grooves of the rails 13 and in the channels of member 12, mount the carriage on the rails 13 for movement to right or left (Figs. 1 and 3). The platen 15 is rotatably mounted in end plates 11 as is usual in the art.

Secured to the rear of the base 10 is a frame casting 16 which extends to right and left (Figs. 1 and 3) beyond the base of the machine on each side a distance equal to approximately half of the width of the base. Mounted on the frame 16 near the right hand rear corner of the machine (Fig. 1) is a ribbon supply spool 17 on which is wound the ribbon 18. Ribbon 18 is passed around a pulley 19 journaled on a stud 20 carried by the right hand end of frame 16 with reference to Fig. 1 or the left hand end referring to Fig. 3 and then is led to the right in Fig. 3 over the right hand rear ribbon guide 21 secured to an arm 22.

The ribbon guide 21, as shown in Figs. 7 and 8, comprises a short curved strip of metal bent downwardly, forwardly, and upwardly with a smooth curve whereby the ribbon is deflected toward the front of the machine. Ribbon guide 21 is mounted on a bracket 23 which is attached to the side of the arm 22 by means of screws 24, the bracket 23 having lugs 23a secured to the ribbon guide 21. Lugs 21a formed in the ends of narrow strips secured to the ribbon guide 21 maintain the ribbon on the ends of the guide whereby the ribbon in its feeding movements clings closely to the surface of the guide 21 and is kept from slipping off the ends of the two branches of said guide. It has been found that the ribbon will feed evenly

over the curved surface on the guide 24 without slipping off said surface provided the material comprising the guide is not strained or stretched to any appreciable extent during the process of forming the guide. By means of this curved ribbon guide, it is possible to deflect the ribbon at right angles to its path from pulley 18 without the use of a more complicated system of guide rolls.

10 From the ribbon guide 24 the ribbon is passed forwardly over a pulley 25 rotatably mounted on a stud carried by the arm 22 at a point slightly in the rear of the platen 16. Forwardly of the pulley 25 (see Fig. 1) there is provided a curved 15 ribbon guide 26, somewhat like the guide 24, mounted on a bracket 27 secured to the forward end of arm 22.

The arm 22 is pivoted at 28 on a stud carried by the rear end of an extension plate 29 secured 20 to the right hand plate 11 comprising the carriage (Fig. 1). On the opposite end of the carriage a similar arm 22 and plate 29 are provided. The arms 22 are integrally joined at the rear end of the machine by a tube 30 while at the forward 25 end they are joined by a tie rod 31.

The right hand front ribbon guide 26 is shown in Fig. 9 and comprises a short curved strip of metal bent downwardly, forwardly and horizontally to the left and is secured to the side of arm 30 22 by means of screws 32. Secured to the back of the branch of the ribbon guide which extends horizontally to the left is a member 36a having lugs 36b which extend over the front surface of the ribbon guide so as to keep the ribbon from slipping downwardly off the left hand end of the horizontal branch of the ribbon guide. A lug 36c formed in the ribbon guide serves the same purpose for the vertical branch of the ribbon 35 guide.

40 The arm 22 at the left hand end (Fig. 1) of the carriage, as best shown in Fig. 2 is provided with ribbon guides 24, 26 and a pulley 25 which are located at substantially the same points with reference to the stud 28 on which said arm is pivoted as in the case of right hand arm 22 (Fig. 1). However, the ribbon guides 24, 26 on the left hand arm 22 are so constructed that the corresponding parts of the right and left hand guides are symmetrical with respect to the center 45 line of the machine.

From the right hand front ribbon guide 26 in Fig. 1, the ribbon 18 extends horizontally to the left (Fig. 1) over the left hand front ribbon guide 26, over the left hand pulley 25, and over the 55 left hand rear ribbon guide 24, to a feed roller 33 which is mounted on a stud 34 (Figs. 4 and 5) carried by the right hand end (Fig. 3) of the frame 16. The feed roller 33 is mounted on the stud 34 by means of an anti-friction bearing 35. 60 From the feed roller 33 the ribbon 18 passes to the right (Fig. 1), or to the left in Fig. 3, and is wound upon a take-up spool 36. The take-up spool is shown in section in Fig. 6 and consists of two circular stampings 36a, 36b provided with 65 square holes adapted to slip over the squared portion 37a of a shaft 37 journaled in a bushing 38 pressed into a hole in a boss formed in a frame 16.

One of the members 36a, 36b is secured to a hub 36c having lugs which enter rectangular 70 slots formed in the other member whereby the two members 36a, 36b are rigidly connected for driving purposes but may be separated to remove the roll of ribbon. A thumb screw 39 screwed on the rear end of the shaft 37 holds the two 75 stampings 36a, 36b together on shaft 37, with

the squared portion 37a of the shaft projecting through the square holes in the members 36a, 36b whereby, when the shaft 37 is rotated, the members 36a, 36b will be likewise rotated.

Pressed on the shaft 37, adjacent the squared portion 37a, is a grooved pulley 40 (Fig. 6) over which passes a spring belt 41. As shown in Fig. 3, the spring belt 41 passes over two pulleys like 42 mounted on a bracket 43 secured to the frame casting 16. The belt 42 passes through holes in 10 the casting 16 and the base 19 and around a pulley 40a (Fig. 1) which is mounted on the power roller PR which operates the various mechanisms of the typewriter. Since this roller is always turning while the machine is in use, the storage spool 15 36 comprising the members 36a, 36b, 36c will constantly tend to rotate in a counterclockwise direction (Fig. 3) to wind the ribbon. The belt 41 is not stretched tightly on the pulleys but is slack enough so as to slip when relatively slight tension 20 is reached in the ribbon 18.

Pivoted on stud 44 is a lever 45, one arm of which extends downwardly (see Fig. 3) and is provided with a finger piece 45a by means of which the lever may be rocked clockwise against the tension of a coil spring 46 interposed between the finger piece and a lug 16a formed in frame 16. The coil spring 46 surrounds a stud 47 threaded into a hole in the lug 36a and extending loosely through a hole in the finger 30 piece 45a, the purpose of the stud being to hold the spring 46 in place.

The other arm of the lever 45 extends horizontally (see Fig. 4) and carries a feed roller 48, the latter being mounted on a stud 49 carried by 35 the lever 45 by means of an anti-friction bearing 50. The periphery of the feed roller 48 is surfaced with a band of resilient material 51 such as rubber. The spring 46 tends to rock the lever 45a in a counterclockwise direction (Fig. 3) 40 whereby roller 48 presses the tape 52 firmly against the feed roller 33. Secured to the feed roller 33 is a ratchet 53 with which cooperates a spring pressed pawl 54 mounted on a stud 55 carried by the frame 16 whereby retrograde movement of the feed rollers 33, 48 is prevented.

For the purpose of rotating the feed roller 33 to feed the ribbon 18 in step with the carriage, there is provided a tape 55. The feed roller 33 is provided with two peripheral channels, one of 50 which receives the tape 55 and the other the ribbon 18. One end of the tape 55 is secured to the left hand side of the left hand arm 22 (Fig. 1) and after passing around the tape guiding channel in the pulley 38 passes to the right hand 55 side of the machine (Fig. 1), or to the left in Fig. 3, around a pulley 56 carried by the stud 20 and thence to the right in Fig. 3 and is secured to the right hand arm 22 by means of a bracket 57. The tape 55 is kept taut by means of a coil 60 spring 58 which is anchored to the left hand arm 22 (Fig. 1) and to a clip riveted to the tape 55 a spaced distant from said arm, the spring forming a slight loop 55a in the tape.

The arms 22 are shown in elevated position in 65 Fig. 2 with the upper edges of said arms engaging lugs 29a formed in the extension plates 29, the arms being held in this position by means of wish-bone shaped toggle springs 59 hooked over studs 22a carried by the arms 22 and studs 29b 70 carried by the extension plates 29. The studs are so disposed that the effect of the springs 59 is to press the arms 22 upwardly against the lug 29a when the arms 22 are raised or downwardly against stop studs 29c when said arms are lowered. 75

5 The right hand arm 22 (Figs. 1 and 2) is provided with a finger piece 60 by means of which the frame including the arms 22 and rods 30, 31 may be rocked clockwise in Fig. 2 to cause the ribbon 18 stretched between the guides 26 to be projected downwardly in front of the platen at the writing line.

10 The usual paper ball is provided and consists of arms 61 pivoted at 62 on studs carried by the plates 11 and two rods 63a, 63b, the latter carrying adjustable rollers 64. The paper ball is operated in the usual way by means of springs 65 which, when the paper ball is lowered tend to engage the rollers 64 with the surface of the platen 15. When the ribbon supporting and guiding frame including the arms 22 is raised, the arms 61 of the paper ball rest upon the rod 31 which rigidly joins arms 22. Thus, when the ribbon supporting and guiding member is raised, 15 the paper ball is likewise raised out of cooperation with the platen.

20 The usual paper table 66 (Fig. 1) with adjustable side guide 67 is provided and is of a form commonly used in typewriters. The paper table 25 is pivotally mounted in the carriage, as is usually the case, to permit swinging said table to a position to permit access to the usual marginal stops.

25 The ribbon supply spool 17 is constructed similarly to the take-up spool 36 to permit the supply 30 spool to be separated into two parts for the insertion of a fresh roll of ribbon. The supply spool may be rotatably mounted on frame 16 in the same general fashion as the take-up spool 36 but need not be provided with a pulley like pulley 35 40. In order to prevent the ribbon supply spool from rotating too freely, a brake is provided which takes the form of a leaf spring 68 secured to a lug formed in the frame 16 and projecting between the two members comprising the flanges of the 45 spool 17 into engagement with the periphery of the roll of ribbon. The leaf spring 68 is sufficiently resilient to permit bending thereof downwardly in Fig. 3 far enough to remove the rear half of the ribbon supply spool 17.

50 The operation of the ribbon feeding mechanism will now be described. With the frame comprising arms 22 in raised position, a sheet to be typed upon is inserted in the usual way and the frame 55 22 lowered to bring the ribbon 18 to the writing line. As the typing proceeds the carriage of the typewriter moves from right to left in Fig. 1 and conversely in Fig. 3 step by step. A step by step rotary movement is thereby communicated to the feed roller 33 through the tape 55 to rotate said feed roller clockwise in Fig. 3. The ribbon 18 is the feed in step with the carriage whereby there is no relative movement between the ribbon 18 and the carriage.

55 When the end of a line is reached, the carriage 60 is returned in the usual way, either by hand or by the depression of the carriage return key, causing the carriage to move to the right (Fig. 1) or to the left in Fig. 3. The pawl 53, in cooperation with the ratchet 52, prevents retrograde movement of the feed rollers 33, 48 thereby holding the ribbon 18 against reverse movement. Consequently, the ribbon is moved relatively to the carriage, as the carriage returns, to bring a fresh length of ribbon to the writing line and the 65 amount of relative movement between the ribbon 18 in the carriage will depend upon the extent of return movement of the carriage. In other words, if the marginal stops of the machine are so set as to permit the writing of an 8" line and the line 70 75 is completely written, an 8" relative movement

will occur between the ribbon 18 and the carriage. On the other hand, if only a portion of a line, say 2", is written, calling for a carriage return movement of like amount, the ribbon 18 will be advanced only 2" relative to the carriage. 5

The coil spring 58 maintains only sufficient tension in the tape 55 to rotate the feed roller 33 and is designed to permit the tape 55 to slide freely over the pulley 33 when the carriage is returned, the slight drag due to the friction between the 10 tape 55 and pulley 33 being insufficient to materially retard the return movement of the carriage. Since the take-up spool 36 tends to constantly rotate in a counterclockwise direction (Fig. 3), the ribbon 18 will be wound on said take-up spool as fast as the feed rollers 33, 48 advance the ribbon 18 an increment. 15

A machine embodying the ribbon mechanism described above may be used for a variety of purposes, such as, manifolding, the production of 20 master sheets used in the "Ditto" and "New Process" duplicating processes, and for reproduction by the photo-off-set and other printing processes employing photography.

When it is desired to make manifold copies, a 25 pair of sheets is inserted in the carriage in the usual way with the outer or ribbon copy sheet in front of the ribbon 18 and the carbon copy sheet behind said ribbon. In this case the ribbon will consist of a carbon paper tape so threaded through 30 the ribbon guides and over the various guide rollers that the coated side of the tape faces the platen. After the sheets have been inserted in the carriage, the lever 60 is pressed down causing the carbon tape 18 to move down between the two 35 sheets into position in front of the platen writing line, the paper ball 64 being positioned to press both sheets against the platen above the writing line.

When it is desired to produce a master sheet 40 for the "Ditto" process, the carbon tape will be threaded as above so that the coated side faces the platen and will consist of a hectograph or similar carbon tape whereby the typed impressions on the master sheet may be subsequently 45 transferred to the gelatine blanket in a well known way.

Master sheets for the photo-off set and similar printing processes may be produced in a similar way utilizing a carbon ribbon which has a black 50 coating designed for this purpose.

In the production of master sheets for the "Ditto" process and the photo-off set process, the usual inking ribbon is disabled by positioning the stencil control button or lever to the stencil 55 typing position.

When it is desired to prepare master sheets for the "New Process" method of duplication, the master sheet is positioned so that the tape 18 is between the master sheet and the platen with the 60 uncoated side facing the platen whereby the impressions produced by the type are made on the back of the master sheet and in reverse. A ribbon similar to that used in the "Ditto" process may be used and the regular inking ribbon of the typewriter is also employed to type upon the face of the master sheet as a means of verifying the accuracy of the typed matter. 65

While there has been shown and described and pointed out the fundamental novel features of 70 the invention as applied to a single embodiment it will be understood that various omissions and substitutions and changes in the form and details of the device illustrated and in its operation may be made by those skilled in the art without de- 75

parting from the spirit of the invention. It is the intention, therefore, to be limited only as indicated by the scope of the following claims.

What is claimed is:

5. 1. In combination with the carriage of a typewriting machine, means on said carriage for guiding a ribbon along the printing line, means mounted independently of the carriage for supporting a ribbon storage spool and a ribbon supply spool, means for guiding the ribbon from the storage spool to the carriage and from the carriage to the supply spool, means including a pair of feed rollers and a driving pulley connected to one of the feed rollers, said means being mounted independently of the carriage for feeding the ribbon, and means including a flexible band interconnecting the carriage and the driving pulley whereby to cause said ribbon to be fed in step with the carriage.
10. 2. In a machine of the class described, the combination with the carriage, of ribbon guides mounted in the carriage for guiding the ribbon across the typing line, a support frame mounted at the rear of the machine and extending parallel with the line of travel of the carriage, said frame projecting on each side of the machine the length of the carriage travel, ribbon supply and storage spools mounted in said frame, ribbon guides mounted at each end of the frame for guiding the ribbon from the supply spool to the carriage and from the carriage to the storage spool, means mounted in said frame and comprising a pair of feed rollers for advancing said ribbon, and a resilient connection between said carriage and said feed rollers for rotating same in step with carriage movement whereby the movement of the carriage effects rotation of the feed rollers.
15. 3. In combination with the carriage of a typewriting machine, a ribbon supporting frame pivotally mounted in the carriage, means on said frame for guiding a ribbon along the writing line, means on said frame and located at the rear of the carriage for guiding the ends of the ribbon in opposite directions and parallel with the line of travel of the carriage, means mounted independently of the carriage and at its limits of travel for deflecting the ribbon downwardly and toward the center of the machine, ribbon supply and storage rolls mounted near the center of the machine on which spools the ends of the ribbon are wound, pulleys located at the limits of carriage travel, one of said pulleys having a driving relationship to one of the guide spools, and a flexible band having its ends connected to the carriage and passing around said pulleys, said flexible band being operative when the carriage is moved in one direction to rotate the corresponding ribbon guide spool to thereby advance the ribbon in step with the carriage, and means coacting with the last named guide spool for preventing feed of the ribbon upon the return movement of the carriage.
20. 4. In combination with the carriage of a typewriting machine, a platen mounted on said carriage, a frame mounted on the rear of said machine and extending outboard of said machine on each side thereof, a carriage having its rear portion overlying said frame, guide rollers mounted in the ends of said frame, a pivoted frame mounted in the carriage at a point above the first named frame, ribbon storage and supply spools mounted on the first named frame, said ribbon extending from said spools over said guide rollers and parallel with the carriage move- 5. ment toward the sides of said carriage, means mounted on the second named frame adjacent the pivotal points thereof for deflecting said ribbon at right angles toward the front of the platen, means on the second named frame located at the forward portions of the second named frame for guiding said ribbon in front of the platen and along the writing line, means to displace the second named frame from the position in which the ribbon extends along the writing line to a position in which the ribbon extends above the writing line to permit free insertion of work sheets, means to yieldingly hold the second named frame in either of its alternative positions, a tape having its ends secured to the ends of the carriage so as to form two loops, pulleys at the ends of the first named frame for supporting said loops, one of said pulleys having a driving connection to one of the ribbon guiding spools whereby movement of the carriage in one direction causes the ribbon to be fed in the direction of carriage movement, and means cooperating with one of said spools for preventing reverse movement of the ribbon when the carriage is returned whereby the ribbon is drawn through the guides on the carriage so as to bring a fresh portion of said ribbon to the writing line.
10. 6. In a machine of the class described, the combination with the carriage of a typewriter, ribbon storage and supply spools mounted independently of said carriage and rearwardly thereof, means to support and guide the ribbon for movement relative to the carriage including a frame displaceable from a position in which the ribbon extends along the writing line to a position in which the ribbon occupies a position above the writing line whereby to permit free insertion of a work sheet, a paper bail pivotally mounted in said carriage and cooperating with the work sheet when said frame is in its first named position to hold a work sheet against the platen, said paper bail being elevated with said frame when the latter is displaced to move the ribbon to the second named position.
15. 7. In combination with the carriage of a typewriting machine, a platen mounted on said carriage, a support frame mounted rearwardly of the machine and extending lengthwise of the line of travel of the carriage substantially twice the distance the carriage travels, ribbon supporting spools mounted at the ends of said frame and adapted to support the ends of a ribbon in two horizontal and substantially co-linear straight stretches, means mounted at each end of the carriage for deflecting both stretches of the ribbon at right angles to the line of travel of the carriage and forwardly of the latter to points adjacent the ends of the platen, means on the carriage at the ends of the platen for guiding the ribbon in a straight stretch along the writing line, feeding means for the ribbon mounted at one end of said frame, and a flexible belt connecting said feeding means with the carriage whereby movement of the carriage in a writing direction causes slack in said ribbon produced in one of the horizontal straight stretches by movement of the carriage to be taken up automatically as the carriage moves, and means associated with the feeding means for locking the ribbon against feeding movement when the carriage is returned.
20. 8. In combination with the carriage of a typewriting machine, a platen mounted on the carriage, a ribbon supply spool mounted on said machine independently of the carriage, ribbon feed- 25. 30. 35. 40. 45. 50. 55. 60. 65. 70. 75. 80. 85. 90. 95. 100.

ing means including a pair of ribbon feed rollers mounted independently of the carriage, means to guide the ribbon from the supply spool to the carriage and in front of the platen along the writing line thereof and to said feed rollers, a storage spool for receiving the ribbon from said feed rollers, and means including a flexible band connected to the carriage for actuating the feeding device when the carriage moves.

10. 8. In a machine of the class described, the combination with the carriage, a frame mounted on the rear of the machine and extending parallel with the line of travel of the carriage, feed rollers mounted on one end of said frame, guiding means mounted on the other end of said frame for guiding a ribbon to the carriage and from the carriage to said feed rollers, means connected to the carriage for rotating said feed rollers when the carriage moves in one direction, and means cooperating with the feed rollers to prevent rotation thereof when the carriage is returned.

25. 9. In a machine of the class described, the combination with the carriage, a support frame mounted independently of the carriage and extending along the line of travel of the carriage, ribbon supporting and guiding means mounted on said frame for guiding the ribbon to and from said carriage, said ribbon supporting and guiding 30 means being spaced apart to support the ribbon without interference with the carriage while still permitting free movement of the carriage; ribbon guiding means mounted on the carriage and arranged to guide said ribbon from the first named

guides, in front of the platen, and along the writing line; and feeding means including a pair of feed rollers mounted on said frame for advancing the ribbon when the carriage moves, and a flexible band connected to the carriage for operating the feeding means when the carriage moves in a writing direction.

10. 10. In combination with the carriage of a typewriting machine, ribbon feeding mechanism mounted independently of the carriage including a pair of feed rollers, means to guide the ribbon to and from the carriage to permit free movement of the carriage without fouling the ribbon, means on the carriage for guiding the ribbon along the writing line, a flexible belt connected to said carriage and feed rollers for operating the feeding means when the carriage moves, and a spring connected to said belt and to the carriage for maintaining said belt under tension.

11. 11. In a machine of the class described, the combination with the carriage of a typewriting machine, ribbon supply and storage rollers mounted independently of the carriage, ribbon feeding mechanism mounted independently of the carriage, means for guiding the ribbon to the feeding mechanism and to and from the carriage to permit the carriage to move freely without fouling the ribbon, a flexible belt connected to the carriage and to the feeding mechanism for operating the latter when the carriage moves in a writing direction, and means to yieldingly drive the storage spool to take up the slack produced in the ribbon by said feeding mechanism.

JOHN L. PETZ.
